UNITED STATES PATENT OFFICE.

HERBERT COTTRELL, OF NEWARK, ASSIGNOR TO LOUIS A. SAYRE, OF MADISON, NEW JERSEY.

FRUIT-PARING MACHINE.

SPECIFICATION forming part of Letters Patent No. 340,937, dated April 27, 1886.

Application filed September 21, 1885. Serial No. 177,129. (No model.)

To all whom it may concern:

Be it known that I, HERBERT COTTRELL, a citizen of the United States, and a resident of Newark, county of Essex, and State of New Jersey, have invented a new and useful Improvement 5 in Fruit-Paring Machines, of which the following is a specification.

My invention relates to a rotary cutter for fruit-paring and to the means employed to 10 actuate it.

My object is to provide simple and effective means for supporting the cutter-spindle, and for guiding the movement of the annular cutter toward and away from the fruit during the 15 process of paring and after its completion. I secure this object by journaling the rotary spindle, which carries the cutter in a supporting-arm, and imparting to said arm a variable movement by means of a stationary eccentric 20 cam, which it traverses, by mechanism herein-after described.

Figure 1 represents a front elevation of my improved parer. Fig. 2 represents a plan view. Fig. 3 represents a plan view of the 25 supporting-arm and the cutter-spindle which revolves therein detached. Fig. 4 represents a cross-section of the arm and cutter-spindle drawn on line Y Y of Fig. 3. Fig. 5 represents a cross-section of the arm and spindle 30 drawn on line X X of Fig. 3.

Like letters and figures indicate like parts.

Z is the main frame, carrying the several gear-wheels which actuate the annular cutter 2 and rotary fork T, having tines 10. The 35 fork is rotated through action of driving-wheel M, intermediate gear-wheel, N, and gear-wheel O, the last-named wheel being rigidly secured to the base of the fork-spindle T at 18. The cutter-spindle B receives its variable movement 40 around cam F through driving-wheel M, spindle 14, spur-wheel P, and wheel G, with which the spur-wheel gears. The supporting-arm C is journaled on the face of said wheel G at D D, (shown in Figs. 1 and 3,) and held in its bearings by plate R. The bearing of the supporting-arm C against the cam F is secured by spring 9, one end of said spring being secured to the arm C at 4, the other end to the center of the cam F.

50 It will be seen that the rotation of the wheel

G will carry the supporting-arm of the cutter-spindle B around the cam F, and thereby impart to it the required movement toward and away from the fruit.

While the supporting-arm C is being carried 55 around the cam F the annular cutter 2 is being revolved on its own axis or spindle B. This rotary movement is imparted through driving-wheel M, pinion V, spindle L, having bearings in projecting studs 11 and 12, gear-wheels K and H, the latter loosely journaled on the cam-support and communicating a rotary motion to spindle B through pinion E, carried on the end thereof.

15 is the handle, rigidly attached to driving-wheel M.

S is the standard which supports the machine. This standard is secured to the frame Z by means of a dovetail socket, into which it fits, and to the table by means of a flanged foot 70 and clamping-screw 19 connected therewith.

The supporting-arm C and parts connected therewith are best shown in Fig. 3. The form of the arm is that of a half-sleeve longitudinally, having covered bearings for spindle B 75 at 7 and 8. The outer end of the arm forms the guard 3, which governs the depth of the cut while paring.

A is the cutter-head, carried by spindle B, and 2 the annular cutter thereon.

5 is a slotted piece held by set-screw 6 to the projecting plate 4, made part of arm C. This piece 5 projects under and nearly touches the annular cutter when in place. Its function is to prevent the cutter from leaving the cutter-head and its inner surface from being clogged by the fruit-skins during the process of paring.

85 The annular cutter 2 is simply a strip of thin steel having one of its edges sharpened, and so bent in circular form as to adapt itself to the 90 annular groove in the cutter-head A by its own elasticity. The two ends of the circular strip are kept sufficiently apart on the cutter-head to enable the sharp-edge angle of one end to come in contact with the fruit as the cutter revolves. This contact secures the initial point of the cut. By this form of cutter the tendency to scrape the skin without cutting, noticeable in paring peaches with a rotary knife having a continuous cutting-edge, is entirely removed.

100

I am aware that this form of cutter was the subject of Letters Patent No. 284,823, issued to me September 11, 1883.

What I now claim as new and of my invention is—

1. The combination, with an annular cutter having an opening across its circumference, of supporting-arm C, having projecting plate 4, slotted piece 5, secured to said plate by set-screw 6, spindle B, and means for actuating said arm and spindle, substantially as set forth and described.

2. The combination, with an annular rotary cutter having a break in the continuity of its edge, of supporting-arm C, spindle B, carrying cutter-head A, cutter 2, and pinion E, cam F, spring 9, revolving fork T, and means for actuating said arm, spindle, and fork, substantially as set forth and described. 15

HERBERT COTTRELL.
